UNITED STATES PATENT OFFICE.

HERBERT G. BEEDE, OF PAWTUCKET, RHODE ISLAND.

THREAD-BOARD AND THREAD-GUIDE SUPPORT FOR SPINNING AND TWISTING MACHINES.

No. 910,450.

Specification of Letters Patent.

Patented Jan. 19, 1909.

Application filed December 1, 1905. Serial No. 289,785.

To all whom it may concern:

Be it known that I, HERBERT G. BEEDE, a citizen of the United States, residing at Pawtucket, in the county of Providence and State of Rhode Island, have invented certain new and useful Improvements in Thread-Board and Thread-Guide Supports for Spinning and Twisting Machines, of which the following is a specification.

16 My invention relates to improvements in thread board and thread guide supports for spinning or twisting machines, and the object of my invention is to improve upon the construction of a thread board and thread guide support, as now ordinarily made, and to provide a strong and durable thread board and thread guide support, of simple and inexpensive construction, and adapted to be used in a spinning or twisting machine of any ordinary construction.

20 My invention consists in certain novel features of construction of my improvements, as will be hereinafter fully described.

Referring to the drawing:—Figure 1 is a plan view of a thread board and thread guide support, and other parts connected therewith, embodying my improvements. Fig. 2 is a section, on line 2,2, Fig. 1, looking in the direction of arrow *a*, same figure; the wire 25 thread guide is not shown in section. Fig. 3 is a front view of the parts shown in Fig. 1, looking in the direction of arrow *b*, same figure; the guide wire is not shown. Fig. 4 is a plan view of the metal connecting block, 30 shown in Figs. 1 and 2, detached. Fig. 5 is an edge view of the block shown in Fig. 4, looking in the direction of arrow *c*, same figure. Fig. 6 is an end view of the block, looking in the direction of arrow *d*, Fig. 4. 35 Fig. 7 is a section, on line 7,7, Fig. 4, looking in the direction of arrow *e*, same figure.

In the accompanying drawing, 1 is a detached portion of a frame of a twisting or spinning machine, to which the thread board, 40 carrying the thread guide supports, is hinged. The thread guide board 2 is preferably made of metal, and of angular shape in cross section, as shown in Fig. 2, forming a metal top, and metal front side. The thread board 2 is 45 connected with the front side of the frame 1, near the top edge thereof, by a hinged joint 3. The hinge 3 comprises in this instance a leaf 3', which extends down upon the front side of the frame 1, and between the vertically ex- 50 tending part of a bracket 4, and the front sur-

face of the frame. The leaf 3' is cut out or slotted from its lower end centrally, making an open end slot 3" therein, as shown in Fig. 3, and the vertical portion of the bracket 4 also has a vertically extending opening 4' therethrough, to receive a bolt 5, which passes through said opening 4', and the slot 3" in the hinged leaf 3', and through an elongated opening in the front surface of the frame, and is adjustably secured by a nut 6. 60 A washer 7 preferably extends between the nut 6 and the inner surface of the frame 1, see Fig. 2. The open-ended slots 3" and 4' in the leaf 3' and the bracket 4, respectively, permit of the ready vertical adjustment of the thread guide board 2 and of said bracket 4 on the frame 1 when the nuts 6 are loosened, as also the ready removal of said thread guide board from said frame, when desired. The other leaf 3''' of the hinge 3, which in the 65 normal position of the parts extend substantially parallel to the leaf 3', is secured to the rear portion of a recessed block 8, which is preferably of metal and is arranged beneath and partly inclosed by the angle metal thread board 2, as shown in Fig. 2. The block 8 has in this instance two horizontally extending holes 8' through the rear part thereof, shown by broken lines, and a central opening 8" therein, see Fig. 4. Two screws or bolts 9 70 pass through two holes in the leaf 3''', and through the holes 8' in the block 8, and to their threaded inner ends are fitted nuts 10 which are received in recesses 8^a in the 75 rear edge of the central opening 8" (see Fig. 4), and are thus prevented from turning. The said screws or bolts have slotted heads, as is usual, so that they may be turned by a screw driver.

The block 8 has its ends of reduced thickness, as shown at 8'', see Fig. 5, and each of said ends is provided with a hole 8''' to receive a screw 11 from the upper side of the thread board 2, and the upper side of the thread board 2 is recessed or countersunk to 100 receive the heads of the screws, as indicated in Fig. 2. A nut 12 is fitted to the inner end of each screw 11 and said nuts and screws secure the block 8 to the thread board 2. Recesses 8^b in the block 8, (see Fig. 6) receive 105 the nuts 12 and prevent them from turning, said nuts closely fitting said recesses.

The horizontally extending portion 4" of the bracket 4, forms a rest or support for the thread board 2, to hold it in its proper hori- 110

zontal position. The raising or lowering of the bracket 4, in a vertical plane, by loosening the bolt 5, will raise or lower the thread board 2 and the block 8 attached thereto.

5 It will be understood that there will in practice be only one of the connecting blocks 8, which form the attachment of the thread board 2, through the hinged joint 3, to the frame 1, for about every ten spindles, more 10 or less.

The thread guide support of my improved construction consists preferably of two separate metal plates 13 and 17, preferably of sheet metal. The upper plate 13 has in this 15 instance formed on its inner edge two curved portions 13', to form sockets for the hinge pin 14. The plate 13 also has a central opening therethrough to receive a bolt 15. The side and front edges of the plate 13 are preferably bent downwardly, to form a vertically extending flange 13", see Fig. 3, extending around the edge of the plate. The flange 13" on the front edge, at its central portion, has a notch 13'" therein, see Fig. 3, 20 through which the thread guide wire 16 passes. The plate 17, forming the under part of the thread guide support, preferably extends just within the flanged edge 13" on the plate 13. The rear edge of the lower 25 plate 17 is extended in this instance at its central portion, and is cut through and bent or struck out downwardly, as shown at 17', in Fig. 2, in such a manner that the inner edge of said downwardly extending portion 30 will bear against the lower portion of the metal plate 18, secured by screws 19 to the front side of the thread board 2, and acts to hold the thread guide support in a horizontal position. The metal plate 18 has formed on 35 its upper edge the curved portions 18', forming sockets, in this instance three in number, in line with the sockets 13', to receive the hinge pin 14.

The thread guide wire 16 has on its inner 40 end, which extends between the two plates 13 and 17, an elongated loop, 16', through which extends the bolt 15, and on the lower end of the bolt 15 is a nut 20, which serves to secure the plates 13 and 17 together, and 45 also to secure the thread guide wire 16 between said plates.

By means of the elongated slot 16' at the inner end of the guide wire 16, the wire may be moved in or out, when the nut 20 is 50 loosened to adjust the position of the guide eye 16" on the outer end of the wire, as desired.

By means of the hinges 3, the thread board 2 may be raised to a vertical position, relative to the frame 1, and with it will be raised 55 the thread guide supports, of which there is one for every spindle.

By means of the hinge which connects the thread guide support to the thread board 2, 60 the thread guide support may be raised into

a vertical position, relative to the thread board 2.

The advantages of my improvements will be readily appreciated by those skilled in the art. I provide a thread board, and 70 thread guide supports, of improved construction, which are strong and durable, and inexpensive to make. By means of the flat, slotted end on the thread guide wire 16, the thread guide wire is held in its proper position, and may be moved in or out as desired. 75

It will be understood that the details of construction of my improvements may be varied if desired.

Having thus described my invention, 80 what I claim as new and desire to secure by Letters Patent is:—

1. In a spinning or twisting machine, a thread guide support, consisting of two metal plates, the upper plate having portions thereon for the hinge pin, and a downwardly extending flange on the side and front edges thereof, and the lower plate extending within the flanges on the upper plate, and having a downwardly and rearwardly extending 85 struck-out portion thereon to engage the front of the thread board, and a bolt extending through holes in said plates to secure them together.

2. In a spinning or twisting machine, a 90 thread guide support, consisting of two metal plates, the upper plate having portions thereon for the hinge pin, and a downwardly extending flange on the side and front edges thereof, and the lower plate extending within the flanges on the upper plate, and a bolt extending through holes in said plates to secure 95 them together, and to secure the guide wire between them.

3. In a spinning or twisting machine, a 100 thread guide support, consisting of two metal plates, the upper plate having portions thereon for the hinge pin, and a downwardly extending flange on the side and front edges thereof, and the lower plate extending within 105 the flanges on the upper plate, and a bolt extending through holes in said plates to secure them together.

4. In a spinning and twisting machine, the combination with the machine frame provided with a hinge, a thread board, a recessed block, screws or bolts connecting said block with one leaf of said hinge and with said thread board, nuts on said screws or bolts fitted in recesses in said block and thereby prevented from turning with said screws or bolts when the latter are tightened or loosened, and a thread guide connected 115 with said thread board.

5. In a spinning and twisting machine, the combination with the machine frame provided with a hinge, a thread board, a recessed block, screws or bolts connecting said block with one leaf of said hinge and with 120 said thread board, nuts on said screws or 125 bolts fitted in recesses in said block and thereby prevented from turning with said screws or bolts when the latter are tightened or loosened, and a thread guide connected with said thread board.

- bolts fitted in recesses in said block and thereby prevented from turning with said screws or bolts when the latter are tightened or loosened, a thread guide support having a 5 hinged connection with said thread board and a thread guide carried by said support.
6. In a spinning or twisting machine, a thread guide support consisting of two metal plates, the upper plate having curved portions thereon for the hinge pin, and a downwardly extending flange on the side and front edges thereof, and the lower plate extending within the flanges on the upper plate and having a downwardly and rearwardly extending struck-out projection thereon to engage the front of the thread board, and a bolt extending through holes in said plates, to secure them together, and to secure the guide wire between them.
- 10 7. In a spinning and twisting machine, the combination with the machine frame provided with a hinge, a thread board, a recessed block, screws or bolts connecting said block with one leaf of said hinge and with said thread board, nuts on said screws or 25 bolts fitted in recesses in said block and thereby prevented from turning with said screws or bolts when the latter are tightened or loosened, a thread guide support having a hinged connection with said thread board 30 and consisting of two plates the upper of which is provided at its front and side edges with a downwardly extending flange and the lower of which is fitted within said flange and is provided with a downwardly and rearwardly extending projection to coöperate with an abutment or stop on the said thread board, a bolt for securing said plates together, and a thread-guide clamped between 35 said plates.
